UNITED STATES PATENT OFFICE.

HARRY B. ARNOLD, OF NEW BRITAIN, CONNECTICUT, ASSIGNOR TO NATIONAL SPRING BED COMPANY, OF NEW BRITAIN, CONNECTICUT, A CORPORATION.

EXTENSION-BEDSTEAD.

No. 893,221.

Specification of Letters Patent.

Patented July 14, 1908.

Application filed March 19, 1908. Serial No. 422,036.

To all whom it may concern:

Be it known that I, HARRY B. ARNOLD, a citizen of the United States, residing at New Britain, in the county of Hartford and State 5 of Connecticut, have invented certain new and useful Improvements in Extension-Bedsteads, of which the following is a specification.

My invention relates to improvements in 10 extension bedsteads and the main object of my improvement is efficiency in operation, particularly with reference to ease and convenience in opening and closing the bed to change it from a couch to a bedstead and 15 vice versa.

In the accompanying drawing:—Figure 1 is a plan view of my bedstead when opened up for use as a bedstead. Fig. 2 is an elevation of the same as viewed from the under side of 20 Fig. C. Fig. 3 is a like elevation of the same when closed up for use as a couch, together with broken lines showing an intermediate position of the moving parts. Fig. 4 is an enlarged elevation showing one corner of my 25 extension bedstead as viewed from the left in Fig. 1. Fig. 5 is an elevation of the right hand upper corner, (Fig. 1,) of the bedstead or main bed section.

My bedstead is of the class in which two 30 opposite edges of a fabric are attached to opposite fabric supporting bars between which the fabric is usually stretched. As shown, the fabric is composed of a metallic net work 5 with springs 6, at the opposite edges. This 35 is the ordinary form of the "National wire fabric" for receiving and supporting a mattress upon a couch or bed, and any ordinary mattress supporting means may be substituted for the particular fabric herein shown. The 40 springs which constitute two opposite edges of the mattress supporting means in the main bed section A, are connected with the two fabric supporting bars 7, said bars being preferably formed of angle iron and 45 perforated to receive the hooked ends 8 of the springs 6 as best shown in Fig. 5. The ends of these bars 7 are connected to corner irons 9, which extend downwardly in the form of legs and have their lower ends connected with any suitable brace, as for example the bars 10, which, as shown, constitute the lower side of a rectangular frame, the other sides of the said frame being formed by the fabric supporting bars and legs. To the

lower ends of the legs ordinary casters 11, 55 having swiveling frames, are attached.

The two rectangular frames each having a fabric supporting bar are connected together at the desired distance apart by means of bar supporting rails 12, and tie braces 13 so that 60 the fabric is stretched between the two rectangular frames. I have shown only a portion of the fabric, but in use it will extend substantially the length of the fabric supporting bars 7, 7. These rails and tie braces may be 65 of any desired length, the construction and operation being precisely the same whether they are longer or shorter. For convenience of illustration, I have shown them relatively shorter than they will ordinarily be made. 70 The rails are set lower down on the corner irons or legs than the fabric supporting bars in order that the rails may not be in the way of the fabric. The two rectangular frames, the rails and braces connecting the said 75 frames and a fabric stretched between the said frames constitute the main bedstead or main bed section. As shown it is substantially of an ordinary construction and of itself is not claimed as my invention. I combine with this old bedstead or main bed section A, (which is complete in itself as a non-extension bedstead,) and extension bed section B, and an opening mechanism C, intermediate the main and extension bed sections 80 and by which mechanism the two bed sections are connected. This extension section has two fabric supporting bars 7^a, 7^a, which are preferably of angle iron and have the fabric attached for substantially their whole length. 90 The outer ends of these fabric supporting bars have corner irons 9^a which also form legs, and to the lower ends of these legs I attach a caster 14, the wheel or roller of which is mounted in a fixed or non-swiveling frame, 95 the axis of which caster wheel is parallel to the rails 12 of the main bed section, so that the caster will always be in a position to roll toward or from the main bed section. The opposite ends of the fabric supporting bars 100 7^a of the extension section have neither legs nor feet. These bars 7^a are connected by a bar supporting rail 12^a and a brace 13^a, attached to the corner irons or legs 9^a as in the main bed section. The length of the rail and 105 brace is such that the fabric supporting bars are a little farther apart than in the main section, so that the extension section may be

- placed on the top of the main section and the respective fabric supporting bars of the main and extension sections be nested one within the other with the vertical and horizontal members of the angle iron in the bars 7^a overlapping the confronting upper corners of the main bed section, as shown in Fig. 4. A brace 15 may be placed diagonally within the corner of the bars 7^a and corner irons or legs.
- 10 From this description it will be seen that the fabric of the extension section is attached to a frame that is in plan view substantially the form of an angular letter U. A pair of brackets or links 16 are rigidly connected together by means of a tubular bar 17 and a strap form of brace or tie 18, so as to form with the said brackets a rigid frame for use as an opening mechanism C by means of which the main and extension bed sections 15 are pivotally connected with each other. The lower ends of the links or brackets 16 are pivoted by a bolt or rivet 19 to the bars 10 on the outside of the main section, while their upper ends are pivoted by a bolt or pin 20 to the fabric supporting bars 7^a of the extension section not far from the legless ends of the said bars. The rigid connection consisting of the bar 17 and tie 18 of the brackets or links 16 is between the pivotal ends of 25 the said links. When so mounted the tubular bar 17 and strap like tie 18 of the extension section pass through the two fabric supporting frames of the main section where they may swing between the several sides of 30 the said frames. I prefer to secure a lug 21, Fig. 4, on the inner face of the brackets so that the vertical member of the angle iron of the fabric supporting bars 7^a may be received between the said lug and end of the bracket 35 and the bolt or pin pass through all three parts, as shown in Fig. 4. The strain of the fabric of the extension section is in part sustained by the said brackets. These brackets are held by their rigid connection at the 40 proper distance apart so as to be out of frictional contact with the fabric supporting frames of the main section and prevent the opening mechanism from dragging or binding on the said main section. If desired a fixed 45 lug or projection 22 may be secured to the main bed section underneath the horizontal member of the angle iron fabric supporting bars of the extension bed section for the said member to rest upon at times.
- 50 As before stated the bedstead is illustrated in Figs. 1 and 2, as extended. In this position, that edge of the extension bed section which overlaps the main bed section rests upon the top of the said main section and is 55 supported thereby, while the opposite edge is supported by the corner iron legs and casters. The opening mechanism is now idle only as it serves to prevent the extension section from moving outwardly from the 60 main section, while the main section prevents the adjacent edge of the extension section from being dropped downwardly. In this position the fabrics of the two sections overlap each other at their meeting edges. In order to open up the bedstead preparatory to contracting it, the operator may grasp either one of the brackets 16 of the opening mechanism C, (or either one of the fabric supporting bars 7^a,) and swing the said brackets on the pivots 19 to lift the inner edge of the extension section and at the same time move it towards the main section, as indicated by broken lines in Fig. 3. As the extension section and opening mechanism are carried beyond the dead center of the opening mechanism, as thus indicated by broken lines, the moving parts swing laterally and downwardly into the position shown by full lines in Fig. 3, in which position the extension bed section rests upon the top of the main bedstead or bed section. I prefer to make the corner iron legs 9^a of the extension bed section so short that when in the position shown in Fig. 4 the non-swiveling casters 14 will be raised a little above the floor and the entire weight of both sections will be carried by the swiveling casters 11 of the main section, whereby the casters of the extension section are always in position to roll to and from the main section and at the same time they do not in any way interfere with the rolling of the complete bedstead in any desired direction on the swiveling casters of the main section. The lugs 22 which project slightly above the top of the fabric supporting bars of the main section, are designed to engage the under side of the horizontal members of the angle iron fabric supporting bars 7^a near the last end of their movement as they are being carried into 65 position on the top of the main section, and thus prevent the spring hooks or other parts of the fabric from catching on the upper corners of the main section when the bed is being closed up.
- 70 By my improvement a very simple and easily operated extension bedstead is produced and with but little difference in the dimensions of the main and extension bed sections. By rigidly connecting the brackets 75 of the opening mechanism at two different points between their pivotal ends, they move in perfect unison when operated through either of the said brackets. The said brackets by means of their rigid connection are prevented from moving towards each other under the strain of the fabric and thus they never bind on the main section no matter how great the strain of the fabric thereon may be.
- 75 I claim as my invention:—
1. In an extension bedstead, the combination of a main bed section with an extension bed section having mattress supporting means stretched thereon and adapted to rest 80

upon the top of the said main section, and an opening mechanism intermediate the said two sections and pivotally connected with both sections for swinging the said extension section into position over substantially the whole of the main section, or laterally therefrom with only one edge resting on the top of the said main section, the said opening mechanism having means for sustaining the strain thereon of the said mattress supporting means and for holding the said brackets at the proper distance apart under such strain, whereby the said brackets swing free of the said main bed section.

15. 2. In an extension bedstead, the combination of a main bed section in the form of a complete bedstead of itself, with an extension bed section having mattress supporting means and a pair of legs at one edge thereof, while the other edge is adapted to rest upon the said main section, and an opening device in the form of a rigid frame intermediate the said two sections and pivotally connected with both sections for swinging the said extension section into position over the top of the said main section and drawing the legs of the said extension section closely to the said main section, or laterally therefrom with only one edge of the extension section resting 30 on the top of the main section while its other edge is supported at a distance therefrom by the said pair of legs.

3. In an extension bedstead, the combination of a main section with an extension section and an opening mechanism pivotally connected with the said two sections, the said opening mechanism consisting of a pair of swinging brackets rigidly connected together above their pivotal connection with the said 40 main section.

4. In an extension bedstead, the combination of a main bed section with an extension bed section having fabric supporting bars

connected at one end of the said two bars by a bar supporting rail, a pair of brackets to 45 which the other ends of the said two bars are pivoted, a bar and a brace by means of which the said brackets are rigidly connected with each other, the said brackets being pivotally connected with the said main frame, and a 50 fabric supported by its opposite edges on the said two bars and stretched therebetween, the strain of the said fabric being received and sustained partly by the said rail and partly by the said brackets.

5. In an extension bedstead, the combination of a main bed section having two fabric supporting frames with an extension section and an opening mechanism intermediate the said two sections, the said opening mechanism being in the form of a rigid frame pivotally connected with both of the said sections and passing through the said two fabric supporting frames of the said main section.

6. In an extension bedstead, the combination of a main bed section mounted upon legs as a complete bedstead by itself, swiveling casters upon which the said legs are supported, an extension section having two fabric supporting bars, a connecting rail between 70 the said bars at the outer edge of the said extension section, and a pair of legs at the ends of the said rail, casters on the said legs having rollers with fixed frames which carry the roller axes in a position parallel to the said rail, and an opening mechanism pivotally connected with both sections for lifting the inner edge of the extension section and moving it to and from the main section while the outer edge is supported on the said legs and 75 casters which are always in the proper position to roll to and from the said main section.
